NUMBERING MACHINE

Application filed October 23, 1926. Serial No. 143,534.

My invention relates to improvements in numbering machines known as the typographical or type-high class usually inserted in chases or forms in printing presses, whereby consecutive numbering of printed sheets will be made for successive impressions.

One of the objects of my invention is to provide means whereby the numbering wheels may be rendered free from the push or operating and the hold fast pawls for rotation manually and for permitting cleaning the spaces between the wheels. Another object of the invention is to provide simple and efficient means for detachably retaining the No. block on the actuating plunger of the machine.

My invention comprises novel details of improvement which will be more fully hereinafter set forth and then pointed out in the claims.

Reference is to be had to the accompanying drawings forming a part hereof, wherein

Fig. 1 is a plan view of a numbering machine embodying my invention;

Fig. 2 is a side view of Fig. 1;

Fig. 3 is a section on line 3, 3, in Fig. 1;

Fig. 4 is a plan view with parts omitted;

Fig. 5 is a detail of the push pawls in wheel operating position;

Fig. 6 is a fragmentary detail of Fig. 5, illustrating a different position of the push pawls;

Fig. 7 is a detail underside view;

Fig. 8 is a section on line 8, 8, in Fig. 2;

Fig. 9 is a detail of the spacer for the wheels; and

Fig. 10 is a detail of a tool adapted to be used in conjunction with the machine.

Similar numerals of reference indicate corresponding parts in the several views.

At 1 is indicated the main frame of the numbering machine comprising a base portion 2 having end supports or uprights 3, 4 spaced apart. At 5 is a plunger having a bore 6 slidable on a tubular guide 7 shown supported in the frame 1 adjacent to the upright 4. The guide 7 may be in the form of a rectangular tube secured by solder or otherwise to the upright 4, and the bore 6 of the plunger will be rectangular to correspond. A shaft 8 is shown supported in the upright 3 and in the guide 7, upon which shaft numbering wheels 9 are rotatively

mounted, said wheels having numeral or other type suitably disposed upon their peripheries in a well known way. The plunger 5 has a slot 5^a receiving the shaft 8. A screw 8^a carried by upright 3 engages shaft 8 to detachably retain it. Within the bore 7^a of guide 7 is located a spiral spring 10, the lower end of which rests against a stop shown in the form of a staple 11, the legs of which may be slid through holes 12, 13 in the upright 4 and the guide 7 to oppose and resist the spring. The lower part of the upright 4 is shown provided with a recess 4^a in its outer portion, within which the outer end or head of the stop or staple 11 may be located, within the outer surface of the upright 4, so as not to interfere with the location of the machine in a printing chase. By inserting a tool into the recess 4^a to engage the outer end of stop or staple 11 the latter may be withdrawn to permit the removal and replacement of spring 10 respecting bore 7^a of guide 7. The upper or outer end of spring 10 is provided with a pin 14 shown having a cone-like or tapering outer end at 14^a to enter a hole 15 in the outer end of head or cap 16 of plunger 5, and by protruding through said hole the end portion of the pin 14 will enter a recess 17 in the undersurface of the type block 18, (Fig. 3). The block 18 has beveled sides 18^a slidably guided for replacement in a transverse undercut groove 19 in the outer surface of the outer end of head or cap 16 of the plunger. There may be two of such grooves 19 disposed at right angles to each other and intercommunicating when the head or cap 16 is removed from the plunger 5, (Fig. 1). The cap is shown secured to the plunger 5 by screw threads at 20, (Fig. 3). By rotating the head or cap 16 its position respecting the plunger 5 may be adjustably varied to accommodate required type high conditions respecting the printing surfaces of the numbering wheels, and in such case the block 18 may be slid out of one of the grooves 19 and replaced in the other groove to accommodate the position of cap 16 when rotated on the plunger for printing the character No., or any other desired character on the block, in proper printing line. A spring 5' carried by the plunger 5 at 5^b is adapted to engage either of four slots 16^a in cap 16 to retain the latter in printing alignment. When the block 18 is to be in 105

serted in a groove 19 it is merely necessary to push it along the groove until the pin 14 is pressed by spring 10 into the recess 17 of the block to retain the latter detachably on the cap or head of the plunger, and when it is desired to remove the block 18 it may be pushed lengthwise outwardly since the tapering or cone-like surface 14^a of the pin will cause the latter to be pushed back against the tension of the spring. A screw at 21 is shown carried by the plunger 5 and is adapted to engage the shaft or rod 8 to limit the outward movement of the plunger by spring 10 when the latter pushes the pin 14 against the cap or head 16 of the plunger. By adjustment of said screw the outward movement of the plunger by the spring may be controlled for regulating the extent of projection outwardly of the printing surface of the block 18 respecting the printing surfaces of the type wheels 9. A recess 4^b in the outer end of upright 4 receives the corresponding portion of plunger 5 when the latter is pushed back during printing.

To each of the numbering wheels 9 is secured a ratchet wheel 22 having a number of teeth corresponding to the type on the peripheries of the numbering wheels and a recess 22^a, in an ordinary way for rotating the numbering wheels. Push pawls are indicated at 23 for operating ratchet wheels 22, (Figs. 5, 6 and 8). A swinging pawl frame 24 is journaled upon the shaft 8 and depends with respect to the numbering wheels and ratchet wheels in an ordinary way to be operated by the plunger 5, as by a pin 25 carried by the plunger operative in a slot 26 in one arm of the lever, (Fig. 8). The push pawls 23 are shown connected together by a member 23^a and provided with bearings, shown in the form of lugs 23^b, journaled upon a rod 27 carried by the frame 24, so that the push pawls may slide along the rod, (Figs. 5, 6 and 8). A coil spring 28 upon the rod 27 bears at one end against a stop 29 on the rod, which may be in the form of a pin or screw, (Fig. 5), and at the other end said spring bears against the member 23^a of the push pawls to normally press the latter into cooperation with the ratchet wheels 22, (Fig. 5). The push pawls operate freely between the arms 24^a and 24^b of frame 24 when the push pawls are in cooperation with the ratchet wheels that are between said arms. The push pawls may be withdrawn from the ratchet wheels by swinging the pawls outwardly, and then the push pawls may be slid along the rod 27 so that the unit pawl 23^c will overlie and engage the arm 24^a of frame 24 to retain the push pawls out of engagement with the ratchet wheels, (Fig. 6), so that the latter may be manually rotated reversely.

On the side of the machine opposite the

push pawls are located holdfast pawls 30 adapted to engage the ratchet wheels 22 to resist reverse rotation of the latter, whereby when the holdfast pawls and the push pawls both engage the ratchet wheels on opposite sides the latter will be firmly held with the type in printing position, and each time the plunger is pressed inwardly during a printing stroke the frame 24 will be pushed downwardly with its push pawls, whereby the latter may engage appropriate teeth of the ratchet wheels for rotating the numbering wheels a space of one tooth on the ratchet wheel during the outward movement of the plunger by means of spring 10 after an impression has been made. The holdfast pawls 30 are journaled upon a rod 31 that is carried by a frame 32 that is journaled upon a rod 33 carried by the main frame 1 in a direction parallel with shaft 8, whereby the frame 32 with the holdfast pawls may be swung away from the ratchet wheels to permit the latter to be freely rotated manually reversely. The pawls 30 have teeth 30' to engage the ratchet wheels, (Fig. 8). Springs 34 are shown coiled around the rod 31 and are shown bifurcated to bear against the adjacent holdfast pawls between which the springs are located, (Fig. 2), each spring being provided with a projecting portion 34^a that bears against the rod 33, whereby tension of the springs will be against the pawls 30 to resiliently press them against the ratchet wheels. The pawls 30 have toes or projections 30'' to engage the frame 32 to limit the forward movement of the pawls when frame 32 is swung away from the ratchet wheels, (Fig. 8). The frame 32 is shown provided with a block-like portion 32^a, one end of which is normally located adjacent to the upright 4, when the holdfast pawls engage the ratchet wheels, and means are provided to retain the frame 32 in the last named position during operation of the machine. I have shown the block-like portion 32^a provided with a locking pin 35 slidable in a bore 36 in said block, said pin being shown provided with a projection 37 operative in a slot 38 in block 32^a, which pin 35 is adapted to enter a recess or hole 39 in upright 4 for locking the frame 32 in operative position. A spring 40 in bore 36 bears against the metal at one end of the bore and against pin 35 to normally push said pin toward upright 4, the projection 37 by engaging the metal at the appropriate end of slot 38 controlling the thrust of pin 35 by spring 40. A beveled or inclined surface at 41 on upright 4 permits the exposed end of pin 35 to ride freely toward the hole 39 when frame 32 is swung toward frame 1. To more rigidly hold the frame 32 I provide a screw 32^c carried by upright 3 to engage the frame 32, (Fig. 2).

The space along the shaft 8, between the arms of frame 24, is longer than the width of the numbering wheels and ratchets when assembled for operation, so that said wheels 5 may be made free from contact with each other to permit the insertion of a tool therebetween for cleaning the contiguous surfaces of the numbering wheels and ratchets, (Fig. 3). I provide a spacer 42, shown in 10 the form of a thin piece of metal, substantially in the nature of a shim, adapted to be inserted and retained between the arm 24^a of frame 24 and the adjacent ratchet wheel 22, such spacer being of such thickness as 15 to suitably fill the space between the arm 24^a and said ratchet wheel to cause the numbering wheels and the ratchet wheels to fit snugly and rotatively together for the printing operation. The spacer 42 is shown provided 20 with recess 42^a in its undersurface, (Figs. 8 and 9), to receive the shaft 8 for desired insertion and removal of the spacer. Means are provided for detachably retaining the spacer 42 in position, for which purpose I 25 have shown the spacer provided with a projection or lug 42^b, extending at right angles to the spacer, for location over the outer end of upright 3, to which latter the projection 42^b may be secured. I have shown the projection 42^b provided with a slot at 42^c to receive the screw 8^a, (Fig. 1). When the screw is secured upon the projection 42^c the spacer will be retained in position between the arm 24^a and the adjacent ratchet wheel 22, so that the numbering wheels will be retained in operative position on shaft 8 and 30 may freely revolve for consecutive numbering. When it is desired to clean the numbering wheels and adjoining ratchet the screw 8^a is released from the projection 42^b and the spacer or shim 42 is pulled out of the machine, thereby providing for space between the numbering wheels and ratchets 35 for the insertion between the latter of a suitable tool for cleaning out the surfaces between the wheels. In Fig. 10 I have illustrated a relatively thin tool 43 having a slot 44 at one end, which may be inserted in the space between a numbering 40 wheel and a ratchet, whereby the tool may be rocked back and forth. The numbering wheels may be rotated when the push pawls and the holdfast pawls have been swung back from the ratchets. After the 45 spaces between the wheels have been cleaned the spacer or shim 42 will be replaced and retained by screw 8^a to keep the numbering wheels in proper relation for operation. The tool 43 is shown provided with a member 43^a, pivoted at 43^b, for use on the machine. 50

In accordance with my invention I provide improvements in numbering machines of the class specified having numerous advantages, in that block 18 may be readily in-

serted and removed and will be retained for printing purposes by means of the spring 10 and pin 14, the numbering wheels may be made free for manual rotation in opposite directions, by first shifting the push pawls 70 and the holdfast pawls from operative position respecting the ratchet wheels, so that the numeral type on the numbering wheels may be readily set in either direction, and by removal of the spacer or shim 42 the 75 numbering wheels are free to permit the insertion of a tool therebetween for cleaning the surfaces between the wheels. Heretofore the numbering wheels, so far as I am aware, have not been mounted for longitudinal 80 movement along their supporting shaft, to enable a tool to be inserted between the wheels for cleaning them, a disadvantage having been that the spaces between the wheels became clogged with foreign matter 85 rendering the wheels uncertain of consecutive rotation, and requiring considerable time and expense in cleaning the machine because it was necessary to dismantle the parts to clean and replace them, whereas in my 90 improvement dismantling of the parts for such purpose is not necessary and considerable time and expense is saved in keeping the machines in desired working order.

My invention is cheap to manufacture, 95 efficient in operation and not liable to get out of order. Changes may be made in the details of construction and relative arrangement of parts set forth, within the scope of the appended claims, without departing 100 from the spirit of my invention.

Having now described my invention what I claim is:—

1. A numbering machine of the class specified comprising a frame having a tubular guide, a spring in said guide provided with a pin having a tapering outer end, a plunger operative along said guide and provided with a head having a hole receiving said pin, said head having an outer guide, 105 a removable block fitted to the guide and provided with a recess to engage the projecting end of the pin, and a stop extending across the bore of the guide to oppose the spring. 110

2. A numbering machine as set forth in claim 1, in which the frame is provided with a transverse hole slidably receiving the stop, whereby when the stop is pulled out of the frame the spring with its pin may be removed from the guide. 120

3. A numbering machine as set forth in claim 1, in which the frame is provided with transverse holes and the stop is in the form of a staple having its legs located in said 125 holes to oppose the spring, the frame being provided with a recess receiving the head of the stop.

4. A numbering machine of the class specified comprising a frame provided with 130

a shaft, numbering wheels and ratchets attached thereto journaled upon the shaft, a pawl frame pivotally supported, push pawls pivotally carried by said frame and slidably supported thereon for movement relatively to the ratchet wheels, one of said push pawls being adapted to engage a member to retain the push pawls out of engagement with the ratchet wheels when the push pawls are slid relatively thereto, a plunger, and means for operating the frame by the plunger.

5. A numbering machine as set forth in claim 4, in which the push pawl is adapted to operate adjacent to an arm of the pawl frame for operating the ratchets, said push pawl being in position to engage said arm when the push pawls have been removed from the ratchet wheels and slid relatively thereto for engagement of said pawl with said arm for retaining the push pawls out of engagement with the ratchet wheels.

6. A numbering machine as set forth in claim 4, in which the pawl frame is provided with a rod and the push pawls are provided with a member slidably supported upon the rod, the frame having spaced arms between which the wheels and the push pawls are adapted to operate, one of said pawls being located in position to engage an arm of the pawl frame when the push pawls have been slid relatively to the wheels to retain said pawls out of engagement therewith.

7. A numbering machine of the class specified comprising a frame provided with a shaft, numbering wheels and ratchets attached thereto journaled upon the shaft, a frame journaled in the first named frame at one side of the numbering wheels, holdfast pawls journaled upon the second frame for engagement with the ratchets, springs cooperative between the last named frame and said pawls, and means to detachably retain said frame with the holdfast pawls in relation to the ratchets for cooperation therewith.

8. A numbering machine as set forth in claim 7, in which the second named frame is provided with a block having a bore, a pin slidable in the bore, a spring to operate the pin, the pin having a projection for its operation, and the first named frame having means cooperative with the pin for detachably retaining the second named frame with the holdfast pawls in cooperative relation to the ratchet wheels.

9. A numbering machine as set forth in claim 7, in which the second named frame is provided with a rod, the holdfast pawls being pivotally supported on said rod, springs carried by said rod and cooperative with said pawls, and means cooperative with the springs for resiliently pressing the pawls against the ratchet wheels.

10. A numbering machine as set forth in

claim 7, in which the first named frame is provided with a rod, the second named frame being pivotally supported upon said rod and provided with a rod, the holdfast pawls being pivotally supported upon said last named rod, springs carried by said rod and cooperative with said pawls, said springs having portions cooperative with said first named rod for resiliently pressing the holdfast pawls against the ratchet wheels.

11. A numbering machine of the class specified comprising a frame provided with a shaft, numbering wheels and ratchets rotatively mounted upon the shaft, means for rotating said wheels for printing consecutive numbers, said wheels being slidably mounted upon said shaft to permit insertion of a tool between the wheels for cleaning their contiguous surfaces, a spacer adapted to be inserted between one of the wheels and an adjacent portion of the machine for retaining the wheels in normal printing relation, and means for detachably retaining said spacer, whereby when the spacer is removed the wheels may move away from one another to permit insertion of the tool therebetween for cleaning them.

12. A numbering machine as set forth in claim 11, in which the spacer is provided with a recess to receive said shaft.

13. A numbering machine as set forth in claim 11, in which the spacer is provided with a projection and the frame is provided with a screw for detachably retaining the projection.

14. A numbering machine of the class specified comprising a frame provided with a shaft, numbering wheels and ratchet wheels rotatively mounted upon the shaft, a pawl frame journaled upon the shaft and provided with push pawls to operate the ratchet wheels, said pawl frame having arms located on opposite sides of the wheels and spaced apart, the length of the space between said arms being greater than the width of the wheels to permit movement of the wheels longitudinally along the shaft, a spacer located between one of said arms and an adjacent wheel for operatively retaining said wheels in normal spaced relation for printing, and means for detachably retaining said spacer, whereby when the spacer is removed the wheels may move along the shaft to provide spaces between the wheels to permit insertion of a tool for cleaning contiguous surfaces of the wheels.

15. A numbering machine of the class specified comprising a frame having a shaft, numbering wheels and ratchet wheels journaled upon the shaft, a pawl frame hung upon the shaft and provided with push pawls to engage the respective ratchet wheels, a plunger operatively connected with said frame, means guiding said plunger

er for reciprocation, an adjustable stop cooperative between the plunger and the shaft for controlling the outward movement of the plunger, and a spring cooperative between the plunger and the frame for moving the plunger outwardly, said stop determining the outward movement of the plunger by the spring.

16. A numbering machine as set forth in claim 15, in which the plunger is provided with a slot receiving the shaft and the stop is in the form of a screw carried by the

plunger in position to engage the shaft to limit outward movement of the plunger.

17. A numbering machine of the class specified comprising a frame having a guide, a plunger operative along the guide and provided with a cap, screw threads connecting the cap with the plunger for adjusting the cap for type high position, and a spring for normally pressing the plunger outwardly.

JAMES H. REINHARDT.
